UNITED STATES PATENT OFFICE.

JOHN SWANSON, OF TROWBRIDGE, ILLINOIS.

MARKER.

1,333,514.

Specification of Letters Patent.

Patented Mar. 9, 1920.

Application filed June 14, 1918. Serial No. 240,019.

To all whom it may concern:

Be it known that I, JOHN SWANSON, a citizen of the United States, residing at Trowbridge, in the county of Shelby and

5 State of Illinois, have invented new and useful Improvements in Markers, of which the following is a specification.

This invention relates to the art of testing seed and especially to testing seed corn, the 10 object being to provide a marker which may be removably secured to an ear of corn to identify the ear while the seed is being tested and to designate the number of seed removed from the ear for testing purposes.

15 To this end the invention includes a pin having upon its shank a flat head containing a number or other designation, which is used to identify the ear to which the pin is attached, the shank of the pin being provided adjacent the head thereof with a squared portion for the reception of a disk, the latter being provided with a squared concentrically arranged opening adapted to fit the squared portion of the shank and 20 also having numbers or other indicia arranged upon one face, these numbers being disposed parallel with respect to the edges of the squared opening, so that one number will be parallel with the number upon the 25 head of the pin.

In the drawings:—

Figure 1 is a front elevation of a marker constructed in accordance with the present invention;

35 Fig. 2 is a sectional view showing the marker applied to an ear of corn, the pin being shown in elevation; and

Fig. 3 is a face view of two of the disks.

In the drawings wherein like characters 40 of reference denote corresponding parts, there is shown a marker which includes a pin provided with a pointed shank 10 and a preferably flat disk like head 11, the latter being provided with suitable identifying indicia as indicated at 12. If desired the shank 10 of the pin may be provided upon 45 its periphery with transversely disposed serrations 13 to aid in holding the pin in position within the ear of corn into which it is 50 adapted to be inserted. The pin is inserted in the end of the ear and the number of indicia 12 thereon is for the purpose of identifying the particular ear which carries the pin.

55 The shank 10 of the pin is provided adjacent the under side of the head 11 with a

squared portion 14, the latter being adapted to removably receive a disk 15. This disk is provided with a concentrically arranged squared opening 16, of a size to fit the 60 squared portion 14 of the shank 10. Arranged around the opening 16 and parallel with the edges of the opening 16 are numbers or other indicia 17 and when positioned upon the shank of the pin the number parallel or above the number on the head of the pin will indicate the number of seed removed from the ear. For example, if the number 4 is directly above and parallel with the number on the head of the pin, it will indicate 65 that four seed have been removed from the ear for testing purposes and the number upon the head of the pin may be used to designate the particular ear from which the seed are removed, this number being placed 70 upon the germinating box or other receptacle for which the seed is planted for experimental purposes. By arranging the numbers upon the disk in the manner shown, one or more numbers may be placed thereon, 75 while the relation of this number with the number upon the head of the pin will, as stated, clearly indicate the number of seed removed from the ear. By arranging the numbers on the disk in the manner shown 80 in Fig. 3 two disks may be used to indicate the numbers from 1 to 8, or if desired numbers arranged consecutively from 1 to 4 may be placed upon a single disk. On the other hand, the configuration of the opening may 85 be changed and an opening of rectangular form provided with the numbers arranged therearound running consecutively from 1 to 6, but the numbers must be arranged parallel with the edges of the opening so that one of 90 the numbers will be disposed parallel with the number on the head of the pin, in order that a record of the number of seed removed 95 from the ear may be preserved.

The invention is susceptible of various 100 changes in its form, proportions and minor details of construction and the right is herein reserved to make such changes.

Having described the invention, what is claimed is:—

1. A marker of the class described embodying a pin having indicia upon the head thereof, a disk removably positioned upon said pin and means for positioning the disk upon the pin to maintain certain of the 110 indicia thereof parallel with the indicia upon the head of the pin.

2. A corn marker embodying a disk provided with an opening therein, numbers disposed around one face of the disk and adapted to designate the number of kernels removed from an ear of corn, a pin comprising a shank adapted for insertion in said ear and through the opening in the disk, a head carried by the shank for contact with

the disk to hold the latter connected to the ear, indicia upon the head of the pin, said indicia coöperating with the numbers on the disk to determine the particular number used and means for preventing accidental relative rotation of the disk and pin.

In testimony whereof I affix my signature. 15
JOHN SWANSON.
